UNITED STATES PATENT OFFICE.

ARTHUR E. WESTBURG, OF JAMESTOWN, NEW YORK.

BRUSH AND MOP HOLDER.

1,033,972.

Specification of Letters Patent. Patented July 30, 1912.

Application filed December 11, 1911. Serial No. 664,930.

To all whom it may concern:

Be it known that I, ARTHUR E. WESTBURG, a citizen of the United States, residing at Jamestown, in the county of Chautauqua 5 and State of New York, have invented certain new and useful Improvements in Brush and Mop Holders, of which the following, taken in connection with the accompanying drawings, is a specification.

- 10 The invention relates to detachable holders for brushes and mops, and the object of the invention is to provide a simple and convenient ratchet and lever mechanism for operating the jaws of a mop or brush holder; and the invention consists in the combination and arrangement of the parts as shown in this specification and the accompanying drawings and pointed out in the claims.
- 15 In the drawings, Figure 1 is a side elevation of the head of the brush or mop holder with a brush clamped therein. Fig. 2 is a plan view of the same without the brush. Fig. 3 is a side elevation of the ratchet and 20 lever mechanism, a portion being broken away to show the action of the ratchet. Fig. 4 is a detail elevation of the ratchet pawl. Fig. 5 is a plan view of the inner side of the clamping lever.
- 25 Like numerals of reference refer to corresponding parts in the several views.

The numeral 10 designates the handle to which the clamping jaws 12 and 13 are attached by means of a ferrule or hollow tip 30 11. The ferrule 11 is preferably a continuation of the clamping jaw 12 so that said jaw extends out stiffly from the end of the handle 10.

The jaw 13 of the clamp is formed with a 35 pair of arms 15 which extend each side of the neck of the jaw 12 and are pivotally attached thereto at 14. A wire link 16 extends through the ends of the arms 15 and along each side of the handle 10 to a clamping lever 17. The lever 17 is preferably 40 made of sheet metal and pivotally attached on opposite sides of the handle 10 to a slidably mounted sleeve 18 by means of trunnions 19, suitable lugs being provided on the 45 semi-circular end of the lever 17 for attach-

ing to trunnions 19. The link 16 is given a sufficient clearance around said trunnions so as to work freely back and forth over the same.

The sleeve 18 is preferably made of sheet 55 metal and slidably mounted on the handle 10 and is not continuous being slotted at 20 the edges of the sheet metal being bent outwardly from the handle 10 into the parallel lugs 21 and a pawl 22 is pivotally attached 60 at 23 between the lugs 21. A toothed strip or rack 24 is attached to the handle 10 so that the teeth 25 extend up within the slot 20 and the pawl 22 is provided with teeth 26 which mesh in teeth 25, but may be turned 65 therefrom permitting the sleeve 18 to slide back and forth freely upon the handle 10 in adjusting jaws 12 and 13 to the brush.

In operating the clamping jaws, the pawl 26 are engaged upon the teeth 25 at 70 that point which causes the lever 17 to draw the jaws 12 and 13 firmly upon the brush or mop cloth and the lever is then sprung from the open position, as shown in Fig. 3, 75 against the handle 10, as shown in Fig. 1, thereby firmly holding the brush or mop cloth yet permitting of their quick and convenient removal by the release of the lever and pawl.

I claim as new—

1. A device of the class described comprising a handle, a jaw attached to said handle, a second jaw pivotally attached across the first jaw to give a leverage, ratchet teeth on said handle, a sleeve slidably mounted on 85 said handle having a slot to receive said ratchet teeth, a pawl pivotally mounted on said sleeve to engage said ratchet teeth, a lever on said sleeve, and link connection between said lever and said pivotally attached 90 jaw to actuate the same and form a clamp.

2. A device of the character described comprising a handle, a jaw rigidly attached to said handle, a second jaw pivotally attached to the neck of said rigidly attached 95 jaw and coinciding therewith to form a clamp, ratchet teeth on said handle, a sleeve slidably mounted on said handle having a lengthwise slot to receive said ratchet teeth, lugs on said sleeve each side of said slot, a 100

toothed pawl pivotally mounted between said lugs to mesh in said ratchet teeth, trunnions on said sleeve, a lever pivotally mounted on said trunnions, and link connection between said lever and said pivotally mounted jaw, substantially as and for the purpose specified.

In testimony whereof I have affixed my signature in the presence of two witnesses.

ARTHUR E. WESTBURG.
